COMBINATION PLASTIC AND METAL
BUILDING CONSTRUCTION

Claude I. Auten, Birmingham, Ala., assignor to
Tennessee Coal, Iron and Railroad Company,
Birmingham, Ala., a corporation of Alabama

Application May 24, 1943, Serial No. 488,248

4 Claims. (Cl. 189—34)

1

The present invention relates to a combination of metallic structural supporting elements and non-metallic structural members such as known forms of hardened plastics interengaged therewith.

An object of the invention is to combine metallic supporting members and hardened, preformed plastic structural members in such a way that they can be effectively integrated in various types of building structures.

A further object of the invention is to combine preformed non-metallic hardened plastic structural members with metallic supporting members in such a way that there is an interengaging overlapping connection between the plastic structural members and the metallic supporting members. The above and further objects and advantages of the invention will be apparent from examination of the accompanying drawings and consideration of the following description.

In the drawings:

Figure 1 is a horizontal section through an upright structural support and related enclosing elements combined with plastic structural member interlocked with the supporting member.

Figure 2 is a view in horizontal section illustrating a modification of the construction shown in Figure 1.

Figure 3 is a horizontal section illustrating a further modification.

Figure 4 is a modification illustrating metallic upright structural building elements having flanged portions for engagement with grooves formed in the opposed edges of adjacent plastic panels.

Figure 5 is a view illustrative of upright metallic structural elements having a portion of a pre-formed plastic structural element interposed therebetween, said element being formed with tongue portions for engagement with suitable grooves formed in coacting panels.

Figure 6 is a view similar to Figure 5 illustrating slight modifications thereof.

Referring first to the embodiment of the invention shown in Figure 1, numerals 10 and 12 represent upright metallic members having flanges 14 and 16 arranged back to back, thus forming a supporting member of T-shaped cross section. Juxtaposed to the flanged uprights there is a preformed, unitary plastic structural member indicated generally at 18 and which is formed with leg portions 20 and 22 spaced apart a sufficient distance to make a fairly snug fit with the exterior faces of the flanges 14 and 16, which constitute the leg of the T-

2

shaped supporting member. The leg 20 has projecting laterally therefrom spaced parallel ribs 24 and 26 jointly forming a groove 28. Symmetrically arranged on the other side of the center line of the member 18 are similar ribs 34 and 36 defining the groove 38. Fitted within the grooves 28 and 38 are suitable plastic panels 40 and 42 which are adapted to form an enclosure for a building or the like. The plastic panels and the member 18 are adapted to be formed by extrusion to the shapes shown.

In the modification of Figure 2, the plastic structural member 48 is formed with legs 50 and 52 embracing the flanges 14 and 16 of uprights 10 and 12. In this embodiment of the invention single tongue-like ribs 54 and 56 are interengaged with grooves 58 and 59 formed in the opposed edges of panel members 60 and 62.

In the modification of Figure 3, a similar construction is illustrated, in which case the extensions 64 and 66 of the plastic structural member engage grooves 68 and 69 formed in the opposed edges of panels 70 and 72. The panels in this form are so arranged that the outer portions thereof are longer than the inner portions so that they substantially meet at the point 73, thus covering the extensions 64 and 66 while the inner portions terminate at points 74 and 76 in close relation to the upright legs 75 and 77.

In the construction of Figure 4, the panels 80 and 82 are formed with grooves 84 and 86 to receive the outwardly extended flanges 88 and 90 of upright metal channel members 92 and 94 arranged back to back.

In the modification of Figure 5, there is a substantially T-shaped plastic structural member having a web 96 disposed between a pair of spaced upright metal angle members 98 and 100. Extending laterally from the web 96 of the plastic structural member are opposite flanges 102 and 104 engaging grooves 106 and 108 formed in the opposed edges of panels 110 and 112 to thus interlock the panels with the plastic structural member.

The modification shown in Figure 6 is similar in many respects to that shown in Figure 5, the chief difference being that there is an extended portion 114 between the adjacent inner edges of the panels 116 and 118.

In the embodiments of the invention illustrated in Figures 1 to 3 inclusive, 5 and 6, the upright metallic supporting member and the unitary preformed plastic structural member, are all secured in assembled relationship by a suitable fastening device such as bolt and nut or

equivalent connection 120. In all of the embodiments of the invention illustrated it will be noted that there is a non-metallic plastic structural member combined and integrated with an upright metallic supporting member and the parts are so arranged that there is an interengaging overlapping connection of the plastic structural member with respect to the metallic supporting member. The plastic structural members in some instances, for example, as shown in Figures 5 and 6, are so arranged that they serve as a heat insulating medium between the metallic members and they thus inhibit the conduction of heat between said metallic elements and the panels such, for example, as the panels 110 and 112.

The plastic structural members such as illustrated at 18 in Figure 1 and at 48 in Figure 2 and similar locations in the other figures are all adapted to be preformed by extrusion. Similarly, the plastic panels referred to may have the described groove and special configurations illustrated, formed therein by known methods of extruding plastics. The various combinations illustrated and described can be readily and economically constructed and erected and will be found in practice to serve their intended functions very effectively.

While I have described quite specifically the details and arrangements of the embodiments of the invention herein illustrated, it is to be understood that various modifications and rearrangements or substitutions of equivalents may be made by those skilled in the art without departure from the invention as defined in the appended claims.

I claim:

1. In a building including panels extending in substantially the same plane and an elongated metallic supporting member of T-shaped cross-section at the juncture of a pair of panels, means for joining said panels to said supporting member comprising a preformed unitary plastic structural member having a longitudinal groove receiving the leg of said metallic supporting member, a portion of said plastic member lying between the edge faces of said panels, and flanges on opposite faces of said plastic member engaged with said panels.

2. In a building including panels and an elongated metallic supporting member of T-shaped cross-section having a flat leg at the juncture of a pair of panels, means for joining said panels to said supporting member comprising an elongated preformed unitary plastic structural member having a plane-faced longitudinal groove free of re-entrant surfaces closely receiving the flat leg of said metallic supporting member, fastening means passing through the walls of said groove and through said leg, and flanges on opposite faces of said plastic member receiving the edges of said panels.

gated preformed unitary plastic structural member having a plane-faced longitudinal groove free of re-entrant surfaces closely receiving the flat leg of said metallic supporting member, fastening means passing through the walls of said groove and through said leg, a portion of said plastic member lying between the edge faces of said panels, and flanges on opposite faces of said plastic member engaging said panels.

3. In a building including panels and an elongated metallic supporting member of T-shaped cross-section having a flat leg at the juncture of a pair of panels, means for joining said panels to said supporting member comprising an elongated preformed unitary plastic structural member

having a plane-faced longitudinal groove free of re-entrant surfaces closely receiving the flat leg of said metallic supporting member, fastening means passing through the walls of said groove and through said leg, and flanges defining channels on opposite faces of said plastic member, said channels receiving the edges of said panels.

4. In a building including panels and an elongated metallic supporting member of T-shaped cross-section having a flat leg at the juncture of a pair of panels, means for joining said panels to said supporting member comprising an elongated preformed unitary plastic structural member having a plane-faced longitudinal groove free of re-entrant surfaces closely receiving the flat leg of said metallic supporting member, fastening means passing through the walls of said groove and through said leg, the edge faces of said panels having longitudinal grooves, and flanges on opposite faces of said plastic member received in the grooves of said panels.

CLAUDE I. AUTEN.
